UNITED STATES PATENT OFFICE.

NIELS ARTHUR INGWORD NIELSEN, OF COPENHAGEN, DENMARK.

COMBINED ELECTRIC LAMP AND ALARM-CLOCK.

1,372,771.

Specification of Letters Patent. Patented Mar. 29, 1921.

Application filed June 21, 1919. Serial No. 305,805.

To all whom it may concern:

Be it known that I, NIELS ARTHUR INGWORD NIELSEN, subject of the King of Denmark, residing at Copenhagen, Denmark, 5 have invented new and useful Improvements in Combined Electric Lamps and Alarm-Clocks, of which the following is a specification.

The present invention is an electric lamp 10 combined with an alarm clock in such a manner that the lamp not only may be lighted and extinguished independently of the alarm clock, but also will be lighted by the latter, as soon as the alarm-mechanism of the clock 15 becomes operative, so that the alarm clock gives not only an acoustic but also an optical signal at a certain predetermined hour, which feature is both practical and convenient, especially when the hour concerned 20 happens to occur during the darkness of the night.

The drawing shows one manner of constructing the invention,

Figure 1 showing the device in rear elevation,

Fig. 2 the adjustable member of the alarm clock for the lamp-switch, in top-view, and

Fig. 3 the same in end-view.

1 (Fig. 1) is an alarm clock of known 30 kind, 2 a case of wood or the like inclosing the same, 3 a tumbler switch which is fastened to the inside of the case 2, and 4 is a lamp-socket inserted in the top of the case and adapted to hold an incandescent lamp 35 5, which is inserted in a not shown electric circuit passing through the switch 3. To the winding shaft for the spring in the alarm mechanism of the clock, there is fastened, instead of the ordinarily used winding key 40 a switch-reversing member consisting of a plate 6 (Figs. 1 to 3) screwed, by means of a sleeve 7 (Figs. 1 to 2), to the winding shaft and supporting, at its edges parallel to the shaft, two plates 8 hinged to the plate. 45 When the reversing member does not co-operate, in the manner further explained below, with the reversing lever 10 of the tumbler switch, the two plates 8 are forced, by two plate springs extending between their 50 free edges and the plate 6, to occupy the positions relatively to the plate 6 as shown in Fig. 3.

The alarm clock and the tumbler switch are so located relatively to one another that

the reversing lever of the latter projects in 55 behind the rear face of the clock. When the lever 10 occupies the lower position shown in Fig. 1, and the alarm mechanism in the clock becomes operative, whereby the shaft of the alarm spring and, thereby, the 60 reversing members 6, 8 are rotated in the direction of the arrow in Fig. 1, then the one of plates 8, which first hits the tumbler lever 10 projecting within reach of these revolving plates 8, will first slide behind the tumbler 65 lever, as shown in Fig. 1, the plate 8 swinging out from the plate 6, and will then take the tumbler lever 10 along, as soon as a suitable (not shown) stop on the plate 6 prevents the plate 8 from turning farther 70 relatively to the same. This will be the case, when the plate 8 occupies approximately the position shown to the right in Fig. 1. The lever 10 is thereby raised into the position shown by dotted lines and snaps from there, 75 in known manner, into its upper (not shown) position, whereby the lamp 5 is lighted. The lever 10 is thereby swung out from the field covered by the plates 8 during their rotation about the shaft of the alarm spring, so 80 that the rotation of the plates may then continue unimpeded.

The switch 3 is opened again, from the outside, by adjustment of a lever 12 connected, by means of a cord-transmission 11 85 or any other suitable device, to the lever 10 in such a manner that a reversal of one of these levers will always cause the other one to be reversed. It will be seen from this that except at the very moment when the alarm 90 clock sounds, the lamp 5 may be extinguished and lighted independently of the alarm clock, simply by reversal of the lever 11, and the lever 10 will then be reversed simultaneously. Even if the lever 10 during its return motion to the current-breaking position, might be moved against one of the plates 8, in case the latter happened to occupy a position rendering this possible, the return motion of the lever will not be prevented, as the plate 8 will simply deflect because, with the shown arrangement of the springs 9 it will be able to deflect, resiliently, 100 in both directions away from the normal position shown in Fig. 3.

The clock 1, the switch 3, the lever 12 and the connecting device between the latter and the lever 10 or its equivalent (in case of

turning switches: the key) may be of any suitable kind and nature, and the shape and quality of the casing 2 is of no concern to the invention as such. The clock and the 5 switch may also be arranged in any suitable manner relatively to one another.

If it be desired, the lever 12 may be omitted and replaced by another switch of any kind connected in parallel with the 10 switch 3, for instance a switch built into the socket 4 in known manner, and adapted to extinguish and light the lamp from the outside. This arrangement suffers from the drawback, however, that the lever 10 must 15 always be reversed separately, after the alarm has sounded.

13 is a thinner plate attached to the plate 6, whereby the spring of the alarm mechanism may be wound by turning the said 20 plate 13.

The reversing members 6, 8 may of course be given other forms than the one shown on the drawing.

Having now particularly described and 25 ascertained my said invention and the man-

ner in which the same is to be performed, I declare that what I claim is:—

In the combination comprising within the same casing an electric lamp, an electric installation switch inserted in a circuit for 30 said lamp, an alarm clock, the alarm winding key of which reverses automatically said switch when turning, and a manipulating lever pivoted in the said casing and adapted to reverse said switch by hand, an alarm 35 winding key comprising a plate, fastened to the alarm winding shaft and parallel thereto, and two plates hinged to the first plate along the edges of same and parallel to the winding shaft and resiliently connected to the first named plate and causing said switch to be closed during the alarm, when turned toward the reversing arm of the switch.

In witness whereof, I have hereunto signed my name in the presence of two sub- 45 scribing witnesses.

NIELS ARTHUR INGVORD NIELSEN.
